UNITED STATES PATENT OFFICE.

MELVIN L. SEVERY, OF ARLINGTON HEIGHTS, AND GEORGE B. SINCLAIR, OF WINTHROP, MASSACHUSETTS, ASSIGNORS TO CHORALCELO MANUFACTURING COMPANY, A CORPORATION OF MAINE.

ELECTRIC MUSICAL INSTRUMENT.

1,104,939.

Specification of Letters Patent.

Patented July 28, 1914.

Application filed February 23, 1906. Serial No. 302,331.

To all whom it may concern:

Be it known that we, MELVIN L. SEVERY, of Arlington Heights, in the county of Middlesex and Commonwealth of Massachusetts, and GEORGE B. SINCLAIR, of Winthrop, in the county of Suffolk, in said Commonwealth, both citizens of the United States, have invented certain new and useful Improvements in Electric Musical Instruments, 10 of which the following is a full, clear and exact description.

This invention pertains to that class of musical instruments wherein a series of sonorous bodies, such as steel or iron strings, 15 are vibrated by the pulsatory magnetic attraction of electromagnets; the magnetic pulsations being produced by a circuit breaking or switching device consisting of uniformly rotating members formed with 20 alternate conducting and non-conducting sections contacting with suitable brushes.

The object of our invention is, first, to neutralize the effect of the lap between said sections and brushes; for we have discovered 25 that when the conducting sections are made equal in span to the non-conducting sections as has always previously been the practice, the contacting thickness of a brush will, in action, so operate that the current will be 30 delivered to the associated electromagnet for a longer fraction of time than it will be cut out therefrom. In consequence of this, the time of action of the magnet would not correctly coincide with the time of approach of 35 the sonorous body toward said magnet. This necessarily diminishes to a substantial degree the string's amplitude of vibration, and hence its loudness of tone, as compared with what it might be were the pull of the 40 magnet to coincide exactly with the inward swing of the string; or at least not to exceed the same.

Our improvement for overcoming this defect consists in shortening the arcs of the 45 conducting sections relative to the non-conducting sections sufficiently to render the dead instants of the magnets equal to, or slightly greater than, their energized instants; and so cause the magnetic pulsations 50 to synchronize with the strings' vibrational swings.

Our second improvement relates to a means for positively actuating a sonorous body throughout its entire vibration by

means of a single make-and-break brush. 55 In our Patent No. 814,878, we disclose a device for this purpose in which each toothed member has two brushes contacting therewith a tooth's distance apart and connected with two magnets at opposite sides of the 60 string or other sonorous body. We have found, however, that it is practically impossible to so perfectly keep the two brushes in adjustment as to prevent them from interfering more or less with each other in their 65 effects upon the string between. By alternately energizing the two magnets of a string with a single brush, such difficulty is removed and no matter how much the brush may wear no injurious effect is caused 70 thereby.

The art or method of producing musical tones necessarily set forth in describing the apparatus of this application, is reserved for co-pending applications, being set forth and 75 claimed in different scope in our co-pending applications Serial No. 273,202 filed August 7, 1905, Serial No. 379,714, filed June 19, 1907, and Serial No. 537,257, filed January 10, 1910.

In our joint application, Serial No. 563,437, filed May 25, 1910 is further disclosure and description of features more or less in common with features of this present application. To the extent that such matters are claimed in said application Serial No. 563,437 they are not claimed herein, but are reserved to said other application. 80

Referring to the drawings forming part of this specification, Figure 1 is a diagrammatic view of a piano string and electric actuating mechanism therefor made in accordance with one form of our invention. Fig. 2 is a diagram of a string and its actuating devices made in accordance with the 90 preferred form of our invention. Fig. 3 is a diagram illustrating said preferred form in connection with a plurality of strings and disks; the latter being shown in edge view instead of in side view as in Fig. 2. Fig. 4 100 is a diagram illustrating certain details of the construction disclosed by Fig. 2.

In Fig. 1, 1 designates a magnetically sensitive string similar to that of a piano; 2 is an electromagnet having a pole presented 105 to said string; 10 is a uniformly rotated disk having conducting sections 12 and high-resistance sections, 13; 26 is the brush

engaging the periphery of said disk, and 20 is the key for switching the pulsatory currents to said magnet. When the key 20 is depressed, the current passes from the 5 source 30 through the wire 33 to the magnet 2; thence through the wire 23, contacts 22, 21, wire 25, brush 26, disk 10, shaft 11, brush 31 and wire 32 back to said source. Of course the instant a tooth or conducting section 12 passes the brush 26 the magnet 2 is 10 energized; and the instant a non-conducting or high resistance section 13 reaches the brush the magnet is demagnetized; thus causing the string to be alternately attracted 15 and released in unison with its designed rate of vibration.

In accomplishing the first object of our invention we lengthen each space 13 until 20 each tooth 12 is substantially shortened as compared with what it would be were the teeth and spaces made all equal. In other words, the angular distance included between the dotted lines 15, Fig. 1, which represents the length of arc when the spaces 25 13 and teeth 12 are equal, is lengthened to that embraced between the dotted lines 16, thereby taking from the peripheral length of each tooth and adding the same to the spaces. In consequence, when the edge of 30 a tooth 12 reaches the heel of the brush 26, current immediately flows through the same, and continues until the opposite edge of the tooth passes out of contact with the toe of the brush; and the time during which the 35 current is thus flowing will exactly equal the time during which no current is flowing; providing the high resistance sections 13 are longer than the conducting sections 12 by twice the lap of the brush. In this manner 40 the energized intervals of the magnet 2 will not exceed the non-energized intervals of the same, and the string will not only be positively moved in one direction of its swing, but will receive no hindering 45 attraction during any part of its opposite swing. Of course no such hindering action will occur if the teeth are made even shorter than above described, but the positive action of the string will be lessened accordingly. 50 Hence it is best to proportion the same as above set forth.

To provide positive actuation of the string in each swing of its vibration, and accomplish the second function of our invention, 55 a core 5 is located at the opposite side of the string from the magnet 2, and a coil 4 placed on a part of said core and connected with a suitable source of electricity; either the one already referred to, or to a separate 60 source 9.

Upon the lower section of the core 5 is a coil 3 connected by means of the wire 35 to the wire 33, and by means of the wire 24 to the wire 23. The wires 33, 35 being 65 joined by the wire 34 to the electromagnet

2, and the wire 23 being connected with the opposite terminal of the said magnet 2, whenever the contacts 21, 22 are brought into touch, both the magnet 2 and the coil 3 are energized. The coil 3 being adapted 70 by its winding and the direction of current delivered thereto to give to the core 5 a polarity opposite to the latter's normal polarity, upon said coil's being energized the polarity of said core will be thus neutralized and there will consequently be no magnetic pull given by it to the string 1. But the magnet 2 being energized as above stated, while the core 5 is impotent, the string will be attracted by said magnet. 75 Then, at the instant the disk 10 presents a non-conducting section to the brush 26, the circuit to the magnet 2 and the coil 3 is broken, said magnet and coil demagnetized, and the core 5 permitted again to attract 80 the string. In this manner, the string is alternately attracted by the magnet 2 and the core 5, and so given a positive actuation throughout its entire vibration. There being some lost energy in this arrangement, 85 we have improved thereon in the way of simplicity of construction and economy of current. This form of our invention is shown in Figs. 2 and 3, where 1 designates the string, and 40 and 41 two electromagnets 90 fixed at opposite sides of said string. Said magnets 40, 41 are so wound that the magnet 41 will have a magnetic pull considerably less than that of the magnet 40, when current is simultaneously delivered to both,—as 95 one-half. Consequently, when current is supplied to both magnets, the stronger pull of the magnet 40 will attract the string toward it more powerfully than the other magnet. Then when the current is cut out 100 from the magnet 40, the magnet 41 will attract the string toward itself; and in this way, the string will receive a pull in alternately opposite directions.

The course of the current is as follows: 110 The key 20 being depressed to put the contacts 21, 22 into touch with each other, current flows from the source 30 through the wire 45, electromagnet 41, wires 44 and 47, said contacts, and wire 46 back to said source. This is the only circuit traversed by the current when the insulating, or high-resistance sections 13 of the disks 10 are in touch with the brushes 26. When, however, the conducting sections, or teeth, 12 reach 115 the brushes 26, then in addition to above-recited circuit, each electromagnet 40 whose key is depressed will receive current through the wire 45, and thence through the wire 32, brush 31, shaft 11, disk and tooth 10, 12, 120 brush 26 and wire 42; the return being through the wires 43, 47, contacts 21, 22 and wire 46 back to the source.

While we have shown and described 125 magnetically attractive strings as our sono- 130

rous bodies, it is quite evident that our invention is equally applicable to many other kinds of magnetically actuated sonorous bodies, as bars, disks, reeds, tubes etc. We 5 do not, therefore, limit ourselves to any particular kind of sonorous body, but desire to be protected in the broadest interpretation of our invention.

In the foregoing description the "lag" 10 of the string or other sonorous body as related to the impelling force, is not noted, for the reason that such lag is more or less a controverted matter, and its injection would simply tend to confusion. The 15 essential point is that whether the two be absolutely in phase or there be a lag of the string or sonorous body, the relationship necessary to generation of the proper tone is made and maintained constant, and the 20 desired result is thereby assured. If there be such lag, it must be uniform, and the movement if commencing later will finish correspondingly later; hence the effect will be that the length of time during which the 25 attractive force is maintained will precisely equal the length of time during which the movement in response to that attraction continues. The foregoing description and the claims are hence to be read with this understanding. 30

What we claim as our invention and for which we desire Letters Patent is as follows, to wit:

1. The combination of a magnetically attractive sonorous body, an electromagnet 35 presenting a pole thereto, a source of electricity, a uniformly rotated member having alternate sections of high and low resistance, a brush contacting therewith, and connections between said source, brush, member and magnet, the peripheral length of 40 said low resistance sections being less than that of the high resistance sections by substantially twice the lap of the aforesaid brush.

2. The combination of a sonorous body, an electromagnet for its actuation, a source 45 of electricity, a member having alternate sections of high and low resistance, a brush contacting therewith, means for giving relative motion to said member and brush, and connections between said source, brush, member and magnet, the length of said low resistance sections being substantially less 50 than that of the high resistance sections by an amount twice the lap of said brush.

3. The combination of a sonorous body, 55 an electromagnet adapted to actuate the same, a source of electricity, a cylindrical member having alternate sections of high and low resistance, a brush contacting with said member, said brush and member having relative motion, and connections between 60 said source, brush, member and magnet, the peripheral length of said low resistance sec-

tions being such that each contact shall be made with its brush throughout an interval equal in duration to substantially the whole of the time consumed by that part of the vibration of said sonorous body wherein the 70 latter is swung toward said magnet, but for no longer time.

4. The combination of a magnetically attractive sonorous body, two electromagnets 75 adapted to actuate the same, a rotating member having alternate high and low resistance sections, a brush contacting with said member, a source of electricity, connections between said magnets, brush, source and member, and a key controlling said connections, said parts being disposed, upon the depression of said key, to bring both of said magnets in circuit simultaneously when one of the conducting parts of said member engages said brush, and to cut out one of said magnets when the non-conducting parts of said member pass said brush. 80

5. The combination of a magnetically attractive sonorous body, an electromagnet disposed with said body in its field, means 90 for delivering timed electric pulsations to said electromagnet, a second electromagnet disposed with said sonorous body in its field but opposite to and in substantial alinement with the first electromagnet, and connections 95 for delivering continuous current to the second electromagnet, the windings of said electromagnets being unlike in resistance and causing the second electromagnet to be weaker than the first electromagnet when both are simultaneously energized. 100

6. The combination of a magnetically attractive sonorous body, an electromagnet disposed with said body in its field, means 105 for delivering timed electric pulsations to said electromagnet embracing a circuit, and a single current-interrupting device having a single brush, a second electromagnet disposed with said body in its field but opposite to and in substantial alinement with the first 110 electromagnet, and connections for delivering continuous current to the second electromagnet, the windings of said electromagnets being unlike in resistance and causing the second electromagnet to be weaker than the first electromagnet when both are simultaneously energized. 115

7. The combination of a magnetically attractive sonorous body, an electromagnet disposed with said body in its field, means 120 for delivering timed electric pulsations to said electromagnet embracing a circuit and a key controlling the circuit, a second electromagnet disposed with said body in its field but opposite to and in substantial alinement with the first electromagnet, and connections for delivering continuous current to the second electromagnet so long as said key maintains said circuit closed, the first 125 electromagnet being wound with much lower 130

- 4
- resistance than the second electromagnet and having a magnetic strength in excess of that of the latter when both are simultaneously energized.
- 5 8. The combination of a magnetically attractive body, two electromagnets presenting their poles at opposite sides of said body, a rotating member having its periphery formed with alternate high and low resistance sections, a brush contacting with said periphery, a source of electricity, a contact and a key controlling it, connections between said key and both of said magnets, a connection between said contact and one pole of 10 said source, a connection between the opposite pole of said source and said member, a connection between said brush and one of said magnets, and a connection between the other of said magnets and said opposite pole.
- 15 9. The combination of a magnetically attractive sonorous body, two electromagnets disposed to actuate the same from opposite sides, a rotating disk having alternate sections of high and low resistance, a single brush contacting therewith, a source of electricity, and connections between said source, electromagnets, brush and disk, including a branch circuit for one of the electromagnets, said disk and single brush being arranged to 20 deliver to one of said electromagnets inter- 35 rupted currents, the other of said electromagnets being energized by an uninterrupted current, whereby said magnets are adapted alternately to attract said sonorous body in opposite directions.
- 10 10. The combination of a magnetically attractive sonorous body, two electromagnets disposed with said body in their fields but in opposition to each other and in substantial alinement, a rotating circular member 40 having its periphery divided into alternate sections of high and low resistance, a brush contacting with said periphery, a source of current, a circuit comprising two branches, one branch including said brush, rotating member and one of said electromagnets, and the other branch including the other electromagnet, said electromagnets being unequal in attractive power, and a circuit controlling device in the common section of said 45 50 circuit.

In testimony that we claim the foregoing invention, we have hereunto set our hands this 16th day of February, 1906.

MELVIN L. SEVERY.
GEORGE B. SINCLAIR.
